OTHER PUBLICATIONS

U.S. Appl. No. 12/689,929, filed Jan. 19, 2010 includes the same drawings as the present design patent application.

Primary Examiner — Ian Simmons

Assistant Examiner — Charles D Hanson

(74) Attorney, Agent, or Firm — Stetina Brunda Garred & Brucker; Lowell Anderson

(57) **CLAIM**

The ornamental design for a collapsible container, as shown and described.

DESCRIPTION

FIG. 1 is a top perspective view of a container of this invention in a vertical orientation;

FIG. 2 is a top perspective view of a container of FIG. 1 in a horizontal orientation;

FIG. 3 is a perspective view of the bottom of the container of FIG. 1; and,

FIG. 4 is a top perspective view of the container of FIG. 1 with a zippered opening in the bottom being open.
